158,184

REAR SEAT WINDSHIELD FOR CONVERTIBLES

Henry K. Edlund, John G. Monjar, George R. Shuman, and Richard De Tamble, Detroit, Mich., assignors to Tonne-Shield Corporation, a corporation of Michigan

Application August 18, 1948, Serial No. 148,176

Term of patent 14 years

(Cl. D14—6)

To all whom it may concern:

Be it known that we, Henry K. Edlund, John G. Monjar, George R. Shuman and Richard De Tamble, citizens of the United States, residing at Detroit, in the county of Wayne and State of Michigan, have invented a new, original, and ornamental Design for a Rear Seat Windshield for Convertibles, of which the following is a specification, reference being had to the accompanying drawings, forming a part thereof, in which:

Fig. 1 is a view in perspective of a rear seat windshield for convertibles, showing our new design; and

Fig. 2 is a front elevational view with portions broken away; and

Fig. 3 is an enlarged fragmentary top plan view; and

Fig. 4 is an enlarged side elevational view with a portion broken away; and

Fig. 5 is a fragmentary rear elevational view; and

Fig. 6 is an enlarged fragmentary front elevational view.

We claim:

The ornamental design for a rear seat windshield for convertibles, substantially as shown.

HENRY K. EDLUND.
JOHN G. MONJAR.
GEORGE R. SHUMAN.
RICHARD DE TAMBLE.
